UNITED STATES PATENT OFFICE.

EMMA HART RIORDAN, OF SOUTH RUTLAND, NEW YORK.

VEHICLE-HUB.

1,297,250.

Specification of Letters Patent. Patented Mar. 11, 1919.

Application filed December 31, 1917. Serial No. 209,752.

To all whom it may concern:

Be it known that I, Mrs. EMMA H. RIORDAN, a citizen of the United States, and a resident of South Rutland, in the county of Jefferson and State of New York, have invented new and useful Improvements in Vehicle-Hubs, of which the following is a specification.

This invention relates to vehicle hubs.

10 An important object of the invention is to provide in a device of the above mentioned character a means whereby the hub may be easily secured upon or detached from a spindle.

15 Another object of the invention is to provide in a device of the above mentioned character a means whereby longitudinal thrust in either direction of the hub with respect to the spindle may be eliminated.

20 A further object of the invention is to provide in a device of the above mentioned character a means whereby a lubricating substance may be confined to such elements of the hub as depend upon perfect lubrication 25 to insure a mechanism efficiency in the operation of the same.

25 A further object of the invention is to provide a device of the above mentioned character which is simple in construction, strong, durable, and reliable in operation.

30 Other objects and advantages of the invention will be apparent during the course of the following description.

35 In the accompanying drawings, forming a part of this specification and in which like numerals are employed to designate like parts throughout the same,

40 Figure 1 is a vertical longitudinal sectional view of the device embodying my invention.

Fig. 2 is a fragmental plan view of the same,

Fig. 3 is a sectional view taken on the line 3—3 of Fig. 1,

45 Fig. 4 is an end view of a nut,

Fig. 5 is a view of the opposite end of the same, and,

Fig. 6 is a detail view of a locking mechanism.

50 In the drawings, wherein for the purpose of illustration is shown the preferred form of my invention, the numeral 10 indicates an axle provided with a collar 11 and the conventional form of spindle indicated by the numeral 12. Upon the spindle there is rotatably mounted a hub 13 provided with a box-

ing or bushing 14. An annular boxing ring formed of any suitable material and indicated by the numeral 15 is carried by the hub 13 and embedded therein adjacent one end of 60 the boxing or bushing 14 as clearly shown in Fig. 1. The other end of the hub 13 is provided with a suitable plate 16 secured therein by any suitable means. This plate is provided with an opening 17 communicating 65 with a recess 18 formed within one end of the hub 13 as shown. This recess 18 is connected with an opening 19 formed within the other end of the hub 13 as shown by means of a passage 20. The passage 20 is 70 adapted to accommodate an elongated rod 21, one end of which extends into the opening 19 and is bent at a right-angle thereto to form a handle 22 which projects upwardly through an opening 23 and provided in an 75 annular band 24 carried upon one end of the hub 13 as shown. A plurality of tongues or lugs 25 preferably formed integral with the band 24 are adapted to project into the opening 23 as shown in Fig. 2, forming in conjunction with a spring member 25' a stop or locking mechanism for the handle 22. This spring member it will be noted is secured to the band 24 within the opening 23 by means of screws 26 or the like. While I have shown 85 the spring member 25' as being secured within the member 23 I wish it understood, however, that the same may be secured upon the outer periphery of the band 24 if so desired. Upon the end of the rod 21 carried within 90 the recess 18 there is secured an abutment 27 adapted to engage one end of a coil spring 28 carried by the rod 21 while the other end of the coil spring 28 is adapted to engage a shoulder 29 formed within the recess 18 as 95 shown. Upon the screw-threaded end 30 of the spindle 12 there is disposed a nut 31 provided with an aperture 32 relatively near the periphery thereof, which nut carries an annular boxing ring 33 adapted to engage the 100 face of the plate 16 as shown. Upon the opposite face of the nut 31 there is disposed a boxing ring 34 similar to that indicated by the numeral 33, which boxing ring is adapted to engage a protruding portion 35 of a nut 105 36 having screw-threaded engagement with a flange 37 mounted upon the outer end of the hub 13 and secured thereto by any suitable means.

110 In use, the operation of the device is as follows: Should it be desired to remove the nut 31 from the screw-threaded end 30 of

the spindle 12, the handle 22 is released from the position shown in Figs. 1, 2 and 6, whereupon the end of the rod 21 is moved under the influence of the coil spring 28 5 into the aperture 32 carried by the nut 31. The nut 36 is then removed and the hub 13 is revolved in an anti-clockwise direction, whereupon the nut 31, rotating with the hub 13 is removed from the screw-threaded 10 end 30 of the spindle 12. Upon the removal of the nut 31 it is readily understood that the hub 13 may be readily removed from the spindle 12. When it is desired to screw the nut 31 to the screw-threaded end 15 30 of the spindle 12 in the position shown in Fig. 1 the nut 31 is slightly run down upon the screw-threaded ends 30 of the spindle and the end of the rod 21 is moved into the aperture 32, whereupon the hub 13 is rotated in a clockwise direction thereby moving the nut 31 to the position shown in Fig. 1. The rod 21 is then moved to the position also shown in Fig. 1 and the nut 36 is screwed into the flange 37, bringing the protruding portion into engagement with the 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330
